Primary Examiner — Brett Miller*Assistant Examiner* — Jessica M Gebhart(74) Attorney, Agent, or Firm — Cowan, Liebowitz & Latman, P.C.; Anastasia Zhadina(57) CLAIM

The ornamental design for a wallet as shown and described.

DESCRIPTION

FIG. 1 is a front perspective view of the wallet showing my design;

FIG. 2 is a front elevation view thereof;

FIG. 3 is a left side view thereof;

FIG. 4 is a rear elevation view thereof;

FIG. 5 is a right-side view thereof;

FIG. 6 is a top plan view thereof; and,

FIG. 7 is a bottom view thereof.

Portions of the wallet shown in broken lines, including unclaimed stitching, form no part of the claimed design.

1 Claim, 7 Drawing Sheets(56)
